CLAIM

The ornamental design for a shoes and box case as shown and described.

DESCRIPTION

FIG. 1 is a front view of the shoes and box case showing my new design;

FIG. 2 is a rear view thereof;

FIG. 3 is a left side view thereof, the right side is a mirror image of the left side;

FIG. 4 is a top view thereof;

FIG. 5 is a bottom view thereof;

FIG. 6 is a top perspective view thereof;

FIG. 7 is a top perspective view of the double shoe case shown in a state of use; and,

FIG. 8 is a front perspective thereof.

The broken lines in the drawings depict environmental structure and portions of the article that make up no part of the claimed design.
